UNITED STATES PATENT OFFICE.

DAVID SUTHERLAND, OF ST. LOUIS, MISSOURI.

CAR-DOOR.

SPECIFICATION forming part of Letters Patent No. 325,218, dated August 25, 1885.

Application filed June 29, 1885. (No model.)

To all whom it may concern:

Be it known that I, DAVID SUTHERLAND, of the city of St. Louis, State of Missouri, have invented certain new and useful Improvements in Car-Doors, of which the following is a full, clear, and exact description, reference being had to the accompanying drawings, forming part of this specification, and in which—

Figure 1 is a front elevation of my improved doors. Fig. 2 is a transverse horizontal section taken on line 2 2. Fig. 3 is a detail horizontal section taken on line 3 3, Fig. 1; and Fig. 4 is a detail vertical section taken on line 4 4, Fig. 1. Fig. 5 is a modification.

My invention relates to doors intended more particularly for refrigerating-cars; and my invention consists in features of novelty herein-after fully explained, and pointed out in the claims.

Referring to the drawings, A represents the door-jamb, or part of a refrigerating-car, and B the doors hinged thereto at C. Above the doors is secured a strip, D, being separated by means of brackets D', depending from the door-jamb, and screw-bolts I, projecting outward from the strip and passing through the lower ends of the brackets, outside of which they are provided with nuts J. The strip is wedge shape in transverse section, as shown in Fig. 4, being wider at its inner than at its outer part. On both its lower and upper face is secured a packing, L, the upper one forming a tight joint between the strip and the door-jamb, and the lower one forming a tight joint between the strip and the doors when the latter are closed. In case these joints become loose by wear, a strip is moved slightly outward by tightening on the nuts J, and thus perfectly tight joints are had at all times at the tops of the doors, and a perfectly-tight joint is made between the doors by means of a similar strip, N, connected to one of the doors by means of spring or other arms O and bolts T. This strip N is also wedge shape in transverse section, and either it or the adjacent edges of the doors are provided with packings T'. (See Fig. 3.) The inner bolts, T, pass through slots in the ends of the spring-arms to allow for horizontal movement of the strip to permit it to be forced inward more or less to insure a tight joint be-

tween the doors. It is forced inward by hand-nuts U on the outer end of screw-threaded rods V, that project from the doors, to which the arms are secured through slots W in the arms.

In Fig. 2 the strip is shown forced in by the hand-nuts, forming a tight joint between the doors, and in Fig. 3 it is shown held out by means of the spring arms, the nuts being turned outward to permit the arms to assume this position.

The doors may be held closed by any desirable means. I have shown vertical sliding bars or catches X, that engage their outer ends with brackets or staples Y, secured to the door-jamb and connected at their inner ends to a central link, Z, pivoted to one of the doors and provided with a lever, Z', by which they are operated, and which has a slot, Z², to engage a lug, Z³, and one of the arms to hold the catches in their outer position into engagement with the said brackets. To disengage the catches from the brackets the parts are moved into position shown by dotted lines.

In Fig. 5 is shown a modification in horizontal section, in which the packing-strip IV is drawn in by means of a screw, I, which passes through the strip and screws in a bracket or lug, D, that is secured to the inner side of the door B. The head I of this bolt is made to fit a key or wrench, and may, if preferred, occupy a counterbore of the strip, so that it does not project beyond the face of the strip.

I² is a collar on the screw I, which bears against the inner side of the strip, so that turning the bolt backward the strip may be forced outward.

I claim as my invention—

1. In combination with the doors, the wedge-shape adjustable strip located above the doors, substantially as and for the purpose set forth.

2. In combination with the doors, the wedge-shape adjustable strip provided with packing-strips and located above the doors, substantially as and for the purpose set forth.

3. In combination with the doors, the wedge-shape strip provided with the packing, and the brackets and screw-threaded rods for adjusting the strip to compensate for wear, substantially as and for the purpose set forth.

4. In combination with the doors, the verti-

cal strip located between the doors and made adjustable, substantially as and for the purpose set forth.

5. In combination with the doors, the vertical wedge shape adjustable strip located between the doors, and the packings between the strip and the doors, substantially as and for the purpose set forth.

6. In combination with the doors, the wedge shape strip located between the doors, the spring-arm connecting the strip to one of the doors, and the nuts for tightening the strip to

compensate for wear, substantially as and for the purpose set forth.

7. In combination with the doors, the wedge-shape strip, the slotted spring-arms connecting the strip to one of the doors, and threaded bolts or rods provided with handles for tightening the strip, substantially as and for the purpose set forth.

DAVID SUTHERLAND.
